CASH CABINET

Estel M. Warren, Clinton, N. C.

Application February 8, 1932, Serial No. 591,700
Renewed September 8, 1934

5 Claims. (Cl. 235—22)

This invention relates to cash cabinets and has for an object to provide a cabinet including a cash drawer, and a desk, the leaf of which is equipped to provide a holder for a ledger sheet upon which entries of sales may be recorded during the day and when the cash is counted at the close of business the sheet with the day's business posted thereon, may be removed and inserted in the ledger, space for which is provided in the desk underneath the leaf.

10 A further object is to provide an inexpensive cash cabinet in which the cash drawer may not be opened until after the warning bell is sounded.

15 A further object is to provide a cash cabinet in which the desk leaf is locked by simple mechanism which also locks the operating push rod of the cash drawer against movement so that both the desk and drawer are simultaneously locked with a single key.

20 A still further object is to provide a cash cabinet so constructed that a chassis containing the operating mechanism for the cash drawer and alarm bell may be assembled with the cabinet so as to be readily removed therefrom for inspection and repairs when necessary.

25 A further object is to provide a cash cabinet of the type described which will be inexpensive to manufacture, may be constructed principally of wood, will be rugged and durable, and will consist of a small number of simple parts which will not easily get out of order.

30 With the above and other objects in view the invention consists in certain novel details of construction and combinations of parts hereinafter fully described and claimed it being understood that various modifications may be resorted to within the scope of the appended claims without departing from the spirit or sacrificing any of the advantages of the invention.

35 In the accompanying drawings forming part of this specification,

Figure 1 is a perspective view of a cash cabinet constructed in accordance with my invention,

40 Figure 2 is a vertical section through the cash cabinet,

Figure 3 is a cross section taken on the line 3—3 of Figure 2,

45 Figure 4 is a detail perspective view of the drawer and bell operating mechanism,

Figure 5 is a cross section taken on the line 5—5 of Figure 2, and

50 Figure 6 is a fragmentary horizontal section taken on the line 6—6 of Figure 5.

55 Referring now to the drawings in which like

characters of reference designate similar parts in the various views, the cash cabinet is shown to comprise a casing including a bottom 10, side walls 11, a back wall 12, and a front wall 13, the top 14 having a rectangular opening therein, the front wall also being provided with a rectangular opening therein.

A cash drawer 15 is slidably mounted on rails 16, secured to the bottom and the top of the casing, as shown best in Figures 2 and 5, and moves through the opening in the front wall 13, as best shown in Figure 1.

15 Mounted on the top of the casing is a desk comprising side walls 17, a back wall 18, and a front wall 19, there being vertical partitions 20 disposed between the side walls and connected at the top and bottom by top and bottom horizontal shelves 21 and 22 to provide pigeon holes, as shown in Figure 1. Hinged, as shown at 23, to the front edge of the bottom shelf 22 is a forwardly sloping leaf 24 which is recessed, as shown at 25, in the front edge to engage over the top beveled edge 26 of the desk front wall 19.

20 All of the above described parts of the cabinet are preferably formed of wood to reduce production cost to a minimum.

25 A pair of hooks 27 are secured to the leaf as shown in Figure 1 to receive a ledger sheet 28 which is supported on the leaf 24, and upon which the sales may be recorded so that at the close of business the posting will have been completed.

30 Disposed in the desk on cleats 29' below the leaf is a partition defining a compartment 29 and preferably formed from a single right angular integral member, but which may be formed by securing two wood strips together at one edge, the strips being of a length to extend transversely across the desk to the side walls 17 thereof and to the front wall 19 thereof and terminating short of the back wall 18 so that a considerable space is left between the compartment and the back wall 18 for a purpose which will presently appear. This compartment may be used to store the ledger in which the ledger sheets 28 may be filed when removed from the leaf 24.

35 As best shown in Figures 2 and 3, the operating mechanism for the cash drawer is contained within a chassis or open front box which is located in the space behind the compartment 29 and at the rear of the cash drawer. The chassis comprises a back wall 30, a top wall 31, side walls 32 and 33 and a bottom wall 34, the latter, and also the side walls being secured stationary by means of screws 35, best shown in Figure 2.

A rock shaft 36 is journaled at its ends in the end walls 32 and 33 of the chassis, and carries a bell crank lever 37, one of the arms of which, as best shown in Figure 4, terminates in an eye 38 which receives the hooked end of a push rod 39 which is of sufficient length to extend forwardly above the top of the cash drawer and slidably pass through a suitable opening in the front wall 19 of the desk and is terminally equipped with a button 40, as best shown in Figures 1 and 2. A helical spring 41 is secured at one end to the hooked end of the push rod and is secured at its opposite end to an eye 42 which is screwed into the rear edge of the top 14 of the cash drawer compartment. The spring holds the push rod at its forward limit of movement.

Referring again to Figures 2 and 4, it will be seen that the top edge of the rear wall of the cash drawer is provided with a wear plate 43. A hook catch 44 is pivoted by a hinge 45 to the rear wall 38 of the chassis, the hook being of sufficient length to present its bill 46 upon the front edge of the wear plate, when the hook is in normal or gravitated position, and lock the cash drawer at its rear limit of movement in the cash drawer compartment.

A trip link 47, best shown in Figure 3, is fixed to the rock shaft and terminates in a right angularly disposed pin 48 which underlies the catch, as best shown in Figure 2. When the push rod 39 is actuated, the bell crank 37 will rock the shaft 38 to tip up the trip link and raise the catch to disengage the hook thereof from the wear plate 43 and release the cash drawer. The cash drawer is immediately shoved outward to its forward limit of movement by means of a helical spring 49, best shown in Figure 2, disposed between the rear wall of the cash drawer and an abutment 50 which rises from the bottom 34 of the chassis. When the cash drawer is being manually closed in the usual manner, the spring is tensioned for the next operation.

To operate an alarm at each opening of the cash drawer, a bell 51 is mounted on the top 31 of the chassis and a lever 52 is pivoted immediate its ends, as shown at 53, on the top of the chassis, there being a helical spring 54 secured terminally to the lever and to the top of the chassis to hold a striker 55 on the end of the lever in contact with the operating button 56 of the bell.

The opposite end of the lever is engaged underneath the hooked end 57 of a link 58, as is shown in Figures 3 and 4, the lower end of the link being provided with a right angularly disposed pivot 59 which is passed through an eye 60 in the rearwardly extending arm of the bell crank lever 37. When the push rod is operated the bell crank will pull down the link 58 to rock the lever 52 and raise the striker 55.

For shifting the link 58 laterally to free the spring controlled lever 52 so that the latter will strike the bell operating knob, a cam surface 61 is formed on the inner edge of the link 58 to engage the rear end wall of a slot 62 formed in the horizontal leg of an angle iron 63 which is fixed to the back wall 38 of the chassis, the cam surface being held in intimate contact with the end of the slot by means of a helical spring 64 which is terminally connected to the link 58 and to a pin 65 secured to the rear wall of the chassis.

As will be seen by referring to Figure 2, a stop pin 66 is provided on the push rod 39 to engage with the rear face of the desk front wall 19 and limit upward movement of the link as well as

limit movement of the bell crank and push rod under the influence of the push rod spring 41.

It is desirable that the bell be struck just before the cash drawer is opened, and for this purpose the trip link 47 and pin 48 thereof are so arranged on the rock shaft 36, and the bill 46 of the catch 44 is made of such length that disengagement of the bill 46 from the wear plate 43 is delayed until after the cam 61 on the link 58 has operated to release the lever 52 to strike the bell.

It is desirable that the desk and cash drawer be locked by the single operation of locking the desk and for this purpose, as best shown in Figure 5, I provide a lock 67 of the type usually used to hold closet doors closed, the bolt 68 of the lock projecting in rear of a lateral pin 69 carried by the push rod 39 and preventing the push rod from being actuated when the bolt is locked by turning the key, not shown, in the lock 67. The leaf 20 of the desk is also locked when the bolt is in operative position by means of a right angle bolt 70 which is slidably fitted in a guide 71 secured to the rear face of the front wall 19 of the desk and connected to the bolt 68 by a link 72. The bolt 70 projects upwardly through an opening 73 in the bottom of the ledger compartment 29 and is terminally provided with an angularly disposed lip 74 which hooks over a Z keeper 75 on the leaf and holds the leaf 24 against being raised.

For cushioning the cash drawer against shock when being opened by the spring 49, it will be seen by referring to Figure 6, that a helical spring 76 is secured at one end in a recess formed in a housing 77 arranged at the front of the cash drawer compartment, the free portion of the spring extending in advance of the housing into the path of movement of a block 78 which is secured by screw 79 or otherwise, to the side of the cash drawer. The block impinges against the spring and presses the spring to slow up the cash drawer and bring it to rest without shock or jar at the forward limit of movement. There are, of course, two of these springs, one on each side of the cash drawer compartment.

As best shown in Figure 1, a pencil holder 80 is secured to the side wall 17 of the desk to support a pencil 81 which may be permanently attached to the desk by means of a cable 82.

From the above description it is thought that the construction and operation of my invention will be fully understood without further explanation.

What is claimed is:

1. A cash cabinet comprising a base casing, a cash drawer slidably mounted therein and spring controlled to move through the front of the casing, an open front box forming a chassis disposed upright in the base casing at the rear of the cash drawer, a desk mounted on the base casing and receiving the top portion of the chassis, a compartment in the desk in front of the chassis and above the cash drawer, a hinged leaf for the compartment, a bell on the top of the chassis, mechanism housed in the chassis for sounding the bell and releasing the drawer to be opened by its controlling spring, and a spring-controlled push rod for actuating said mechanism disposed between the compartment and the cash drawer and extending through the front of the desk at one end and entering the chassis at the opposite end.
2. A cash cabinet comprising a base casing, a cash drawer in the casing, a box-like chassis in

- the casing at the rear of the cash drawer, an abutment within the chassis, a spring confined under tension between the abutment and the rear wall of the cash drawer for opening the cash drawer, a hooked catch pivoted to and extending forwardly from the chassis and engaging over the rear wall of the cash drawer to hold the cash drawer closed against the tension of said spring, a rock shaft carried by the chassis and extending parallel with the rear end of the cash drawer, a lever carried by the shaft, a push rod connected to said lever for rocking the shaft and extending forwardly above the cash drawer, and an arm carried by the rock shaft having a laterally extending pin engaged underneath the hooked catch to dislodge the catch from the cash drawer when the rock shaft is actuated to permit the cash drawer to be opened by its controlling spring.
3. A cash cabinet comprising a base casing, a cash drawer in the casing, a spring for opening the cash drawer, a chassis in the casing in rear of the cash drawer, a bell mounted on the chassis, a spring-controlled striker for sounding the bell pivoted on the chassis, a rock shaft journaled in the wall of the chassis underneath the bell, a bell crank on the rock shaft, a push rod connected to one of the arms of the bell crank, an upright link pivoted at its lower end to the other arm of the bell crank and terminating at its upper end in a hook normally engaged over the free end of the striker whereby to rock the striker when the rock shaft is actuated, a bracket carried by the chassis forming a guide for the link, a cam on the link engaging the bracket to move the link laterally when the rock shaft is actuated to dislodge the hooked end of the link from the striker and permit the striker to be moved by its controlling spring to sound the bell, and means operatively connected to the rock shaft to release the cash drawer to be opened by its controlling spring after sounding of the bell.
4. A cash cabinet comprising a base casing, a cash drawer therein, a desk mounted on top of
- the casing, a chassis in the base casing at the rear of the cash drawer and extending up into the desk, a push rod carried by the front wall of the desk and entering the chassis, a bell on the chassis, a spring on the chassis for opening the cash drawer, a rock shaft carried by the chassis, a bell crank carried by the rock shaft, striking mechanism operatively connected to one arm of the bell crank for sounding the bell when the rock shaft is operated, a pivoted catch carried by the chassis for holding the cash drawer closed, and a lever carried by the rock shaft for dislodging the catch to permit the spring to open the cash drawer, said catch having a hooked terminal of such length as to delay disengagement with the cash drawer until after the bell sounding mechanism has operated.
5. A cash cabinet comprising a base casing, a spring-controlled sliding cash drawer therein, a chassis in the casing in rear of the cash drawer, a desk mounted on top of the casing and receiving said chassis, a spring controlled push rod projecting through the front wall of the desk and at its rear end entering the chassis, a bell carried by the chassis, a rock shaft carried by the chassis, an operative connection between the bell and rock shaft for sounding the bell when the rock shaft is moved, a crank carried by the rock shaft connected to said push rod for connecting the push rod and shaft to move as a unit, means operatively connecting the rock shaft to the cash drawer for holding the cash drawer closed against the tension of its controlling spring, a lock carried by the desk having its bolt projecting toward the push rod, a stop on the push rod engaging said bolt when the lock is locked to prevent opening of the cash drawer, said desk having a pivoted leaf, and locking means between the pivoted leaf and the bolt of the lock adapted to lock the pivoted leaf closed simultaneously with locking of the push rod against movement.

ESTEL M. WARREN.
